PROJECTION APPARATUS

David F. Newman, Freeport, and Robert C. Underwood, Brooklyn, N. Y., assignors to Trans-Lux Daylight Picture Screen Corporation, New York, N. Y., a corporation of Delaware

Application May 24, 1928, Serial No. 280,169

6 Claims. (CL 271—2.3)

This invention relates to a projection apparatus and more particularly to means for maintaining a tape ejected from a ticker in substantially uniform position during projection.

5 It is an object of this invention to provide a projection apparatus mounted adjacent a data-recording device in which the tape passes directly from the ticker to the projection position without the formation of any substantial loop in the tape 10 therebetween.

Another object of this invention is to provide a projection apparatus wherein the tape, after it leaves the projection position, is deflected from its normal path while it is being drawn through 15 the apparatus, whereby the tape in projecting position is substantially taut and smooth.

Another object of this invention is to provide means for locking the tape at a point between the projecting position and the pulling means, whereby 20 by movement thereof is prevented when the ticker is at rest and the tension of the tape has increased.

Further objects will appear from the following description, appended claims and accompanying drawing in which:

25 Figure 1 is a side elevation of an apparatus embodying our invention, the ticker and projection system being illustrated diagrammatically.

Figure 2 is a top plan view of the device constituting our invention.

30 Referring to the drawing in which like reference numerals designate like parts, the reference number 1 designates a data-recording device having feed rolls 2, 2, a printing mechanism 3, and the tape guide 4. This data-recording device 35 may be of any suitable type and, since it does not form an essential part of this invention, further description thereof is deemed unnecessary here.

The tape during its ejection from the ticker 1 40 passes from under the guide 4 which, as above pointed out, is part of the ticker mechanism directly to a support 5 in projecting position. The support 5 may be a glass table or a rectangular frame having an opening through which the tape is projected. When in position on the support, 45 images of the indicia on the tape are obtained, by means of the projection apparatus 6, on a screen 7 with the aid of the mirror 8. Since the details of the projection apparatus are not essential to the present invention, description thereof 50 is deemed unnecessary.

From the support 5 the tape may pass over 55 guide rolls 9 and 9' or other suitable means such as rods, pins and the like. In advance of the guide roll 9' there is mounted a standard 10 on which there is pivotally disposed a bell-crank le-

ver 11 having arms 12 and 13. The arm 12 of the bell-crank lever may be formed so that it will ride on the tape between the guide rolls 9 and 9'. If desired, the arm 12 may be formed with bifurcated legs 14 and 15 and carry a roller 16 or any other suitable means to ride or bear on the tape and not prevent its movement through the apparatus. The arm 13 of the bell-crank lever 11 is formed at its free end with a curved or cam-like surface 17 and mounted in cooperative relationship to a 60 table or guide 18. The bell-crank lever 11 is normally urged by means of a spring 19 or any other suitable means to cause the arm 12 thereof to bear upon the tape and to maintain the arm 13 out of contact with the table 18. The tape is 65 drawn through the apparatus by any well-known feeding means of the friction clutch type, designated by reference numeral 20, and operated through gearing by the motor 21.

To prevent the intermittent jerky movement 70 of the tape as it is ejected from the ticker from being transmitted to the tape in projecting position, there is disposed in any suitable manner, as on a bracket 22, a spring tension member at the end of the support adjacent the ticker. This tension member may be of any suitable type. The form illustrated comprises a curved spring member 75 having an inclined body member 23 carrying a looped-end member 24 adapted to engage the tape on the support. This spring permits the 80 tape to be drawn through the apparatus by the tape-pulling means, but prevents it from being pushed through the apparatus by the ticker-ejecting means. If desired, means to adjust the 85 tension of the spring on the support may be 90 provided.

In operation, the tape is intermittently ejected beneath the ticker guide 4 from the ticker 1 and is pulled or drawn in a substantially horizontal direction, in the example shown, directly, without the formation of any substantial loop, on to the projection table or support 5 beneath the looped end 24 of the tension member. When in position on the projection table, images of the 95 tape indicia are obtained on the screen 7 as well understood in the art. The tape, as previously 100 described, is pulled through the apparatus by means of a slip-clutch feeding means 20; that is to say, the pulling roller slips and is rendered ineffective when the tension of the tape is increased. In the normal operation, the roller 16 rides on the tape as illustrated and the arm 13 is maintained out of contact with the table 18. When the tension of the tape is increased, the 105 bend in the tape in advance of the projection 110

table raises the bell-crank lever arm 12, whereby the arm 13 is lowered and brought into contact with the tape on the locking table thereby locking the tape and causing the pulling mechanism 5 to slip and be ineffective, at the same time putting no strain on the ticker. When the tension of the tape has decreased, the arm 12 is lowered and the arm 13 raised, whereby the tape is released from its locked position and rendered 10 capable of being drawn through the apparatus.

The apparatus above described permits the projection action without any substantial intermittent jerky movement, whereby spectators viewing it on the screen may not be subjected to annoyance. This apparatus does not form any substantial loop between the ticker and the projection 15 table.

Since it is obvious that various modifications may be made without departing from the invention, we do not intend to limit ourselves to the exact details above described, except as defined in the claims.

We claim:

1. In a data-recording projection apparatus, 25 means to support a tape in projecting position, means adjacent one end of said supporting means to substantially prevent the intermittent variations and movement in the tape from being transmitted to the tape in projecting position, means in 30 advance of said supporting means and adjacent thereto to maintain the tape taut in said projecting position, and means positioned in advance of said supporting means to lock the tape and prevent its movement through the apparatus when 35 the tension of the tape has increased.

2. In a data-recording projection apparatus, means to support a tape in projecting position, means adjacent one end of said supporting means to substantially prevent the intermittent variations and movement in the tape from being transmitted to the tape in projecting position, and means in advance of said supporting means and adjacent thereto to maintain the tape taut in said projecting position, said last named means comprising 45 a bell-crank lever having one arm thereof riding on said tape and the other arm adapted to

lock the tape and prevent its withdrawal by the feeding mechanism when the first-named arm is raised.

3. In a data-recording projection apparatus, a support to maintain the tape in projecting position, a table in advance of said support, means to deflect a tape passing from said support to said table, and means cooperating with said table to lock the tape and prevent its withdrawal from the apparatus when the tension of the tape has increased. 80 85

4. In a data-recording projection apparatus, a support to maintain the tape in projecting position, a table in advance of said support, a bell-crank lever, one arm of said lever riding on said tape between said support and table, the other arm being in cooperative relation with said table and normally out of contact therewith whereby it may be brought into locking position when the first arm is raised. 90 95

5. In a system of the character described, the combination with a projection support, of means for moving a tape thereacross, there being a tape loop of varying length between said projection support and said means, and a control member coacting with said tape after passage beyond said support, said control member ascending under tape control when the tape loop shortens and descending under the influence of gravity when the tape loop lengthens, said control member comprising means for effecting the anchoring of said tape whereby it may slip with respect to said first named means. 100 105

6. In a system of the character described, the combination with a projection support, of means for moving a tape thereacross, there being a tape loop of varying length between said projection support and said means, and a control member coacting with said tape after passage beyond said support, said control member riding on the tape 110 and holding it against said support, said control member comprising means for effecting the anchoring of said tape whereby it may slip with respect to said first named means. 115 120
